CLAIM

The ornamental design for a shoe heel protector and shield, as shown and described.

DESCRIPTION

FIG. 1 is a perspective view of a shoe heel protector and shield shown in use affixed over the heel of a shoe thereof;
FIG. 2 is a bottom plan view; and,
FIG. 3 is a top plan view thereof.

The dashed line in FIG. 1 represents an exemplary shoe for use with, and forms no part of the present invention.
